UNITED STATES PATENT OFFICE.

JOHN BAPTISTE ABLER, OF GUELPH, ONTARIO, CANADA.

RUBBER GLOVE.

1,341,451.

Specification of Letters Patent.

Patented May 25, 1920.

Application filed February 10, 1920. Serial No. 357,741.

To all whom it may concern:

Be it known that I, JOHN BAPTISTE ABLER, of the city of Guelph, in the county of Wellington, in the Province of Ontario, 5 Canada, have invented certain new and useful Improvements in Rubber Gloves, of which the following is the specification.

My invention relates to improvements in rubber gloves and the object of the invention is to provide means in the rubber glove for retaining the tips of the glove fingers and thumb firmly against the tips of the fingers and thumb of the wearer, when the fingers of the wearer are shorter 10 than the fingers of the glove and it consists essentially of a rubber glove, having a constricted portion in the length of the glove fingers and thumb.

The drawing represents a front view of 20 the rubber glove, showing my peculiar construction of finger and thumb.

1 indicates a rubber glove provided with fingers 2, 3, 4 and 5. Intermediate of their length the fingers 2, 3, 4 and 5 and thumb 25 6 are formed with constricted portions 2^x, 3^x, 4^x, 5^x and 6^x. It very often happens that the glove is of such a size as to fit the hand of the wearer, but in cases where the finger and thumb of the wearer are 30 shorter in proportion to the size of the hand, that the fingers of the glove will not be retained tightly against the tips of the fingers of the wearer. This, it will be understood, is very detrimental, detracting 35 very much from the usefulness of the glove.

In order to overcome this I have provided the constricted portions 2^x, 3^x, 4^x, 5^x and 6^x, which grip tightly around the fingers of the wearer, so that when the glove is drawn on to the hand, should the fingers 40 of the wearer be short in proportion to the fingers of the glove, they may be drawn down on to the fingers of the wearer, so that the lower portions, 2°, 3°, 4°, 5° and 6° will be puckered so as to take up slack in 45 the length of the fingers.

The constricted portions 2^x, 3^x, 4^x, 5^x and 6^x are drawn down toward the crotch between the fingers with portions 2°, 3°, 4° and 5° and the tips of the fingers or thumb of 50 the glove tight against the tips of the fingers of the wearer.

In many operations where the rubber glove is used it is necessary to have the sense of touch fully in the finger tips and 55 if the fingers of the glove are slack at the tips, this sense of touch is to a great extent lost. By my construction, the glove fingers and thumb are held tightly stretched around the finger tips of the wearer so 60 that the tips of the fingers can be used with as much freedom as if no glove was on the hand of the wearer.

What I claim as my invention is:

In a rubber glove, constricted portions 65 formed intermediately of the length of the fingers or thumb adapted to tightly grip the fingers or thumb of the wearer.

JOHN BAPTISTE ABLER.
